LIQUID DISPENSING APPARATUS

Leonard W. Valentine, Baltimore, Md.

Application April 29, 1935, Serial No. 18,901

1 Claim. (Cl. 215—4)

The invention relates to a liquid dispensing apparatus and more especially to a beer dispensing attachment for bottles.

- The primary object of the invention is the provision of an attachment of this character, wherein liquid, such as beer or other beverages, within a vessel or container, such as a bottle, can be readily dispensed at the will of the user of such apparatus or attachment.
- 10 Another object of the invention is the provision of an attachment of this character, wherein the manner of fastening it to the mouth of the bottle is novel in kind, the attachment in its entirety being novel.
- 15 A further object of the invention is the provision of an attachment of this character, wherein through the instrumentality of an air pump the container can be charged with pressure for the dispensing of such contents, the pump being hand operable and is conveniently located for the operation of the same.

A still further object of the invention is the provision of an attachment of this character, which is comparatively simple in construction, 25 thoroughly reliable and efficient in its operation, substantial to afford durability and inexpensive to manufacture.

With these and other objects in view, the invention consists in the features of construction, 30 combination and arrangement of parts as will be hereinafter more fully described, illustrated in the accompanying drawings, which disclose the preferred embodiment of the invention and pointed out in the claim hereunto appended.

35 In the accompanying drawings:

Figure 1 is a side elevation of the attachment constructed in accordance with the invention showing the same applied to a bottle, the bottle being broken away to a considerable extent.

40 Figure 2 is an enlarged vertical sectional view through the attachment, portions of the same being in side elevation.

Figure 3 is a top plan view.

45 Figure 4 is a sectional view on the line 4—4 of Figure 2.

Figure 5 is an exploded perspective view of a clamp ring.

Figure 6 is a fragmentary perspective view of the open mouth end of the bottle.

50 Figure 7 is a side elevation of the attachment.

Figure 8 is an exploded perspective view of a delivery hose and faucet coupling therefor.

Figure 9 is an enlarged sectional view of a modified inlet port.

55 Similar reference characters indicate corre-

sponding parts throughout the several views in the drawings.

Referring to the drawings in detail, A designates generally a vessel, in this instance in the form of a glass bottle, having the contracted neck 5 forming a mouth rim having externally thereof a mutilated bead or rib 11 which extends circumferentially of said rim. This rim 10 externally thereof is also provided with a lug 12 rising from the bead or rib 11 to the top edge of the 10 rim. Adapted to be placed upon the neck 10 of the bottle is a skirted cover 13 of disk form, its skirt 14 being telescoped over the neck 10 and has in the inner face thereof a notch 15 for receiving the lug 12 to prevent the turning of this 15 cover 13 upon the neck of the bottle A. Embracing the neck 10 of the bottle A below the bead or rib 11 is a clamp ring including half circular parts 16 which are formed with an inwardly directed bottom flange 17 this lying beneath the 20 bead or rib 11 on the neck 10 and affords a seat for a resilient gasket 18 to prevent the ring from damaging the bottle neck 10 when wearing such ring. These parts 16 at their ends carry external ears 19 accommodating adjusting screws 20, 25 these being in threaded engagement with the ears on one part and loosely engaged with the ears on the other part of said ring so that in this manner the ring can be made secure about the neck 10 of the bottle A. Swingingly connected 30 with the adjusting screws 20 are binding posts 21 having threaded thereon winged nuts 22, the posts being received in seats 23 provided in the periphery of the cover 13 and in this manner by a tightening of the nuts 22 against the cover 13 35 it can be firmly sealed upon the mouth end of the bottle, there being provided in this cover 13 a sealing gasket 24 which rests upon the upper edge of the neck 10 of the bottle A and thus a seal can be had between the neck 10 and the cover 13 to 40 avoid any leakage at such point.

Secured to the cover 13 is a spigot or faucet-like body 25 having a flow passage 26 therethrough to a discharge nipple 27, this being a part of the body 25 and in this passage 26 is a 45 valve seat 28 engageable by a valve 29 having a feed screw stem 30 so that the valve 29 can be moved to or away from the seat. The stem 30 extends without the body 25 and is fitted externally of the latter with a handle 31 for manual 50 manipulation thereof. The valve 29 controls the flow of liquid through the passage 26 in the dispensing of such liquid from the bottle A. There is fitted in the passage 26 a tube 32 which extends downwardly into the bottle A close to its 55

bottom for directing the flow of liquid within the bottle to the passage 26 in the body 25.

The nipple 27 carries a separable coupling 33 for a supply hose 34 of flexible kind. The hose 5 at its outer end has fitted therewith a dual coupling including the parts 35 and 36, respectively. This coupling including the parts 35 and 36 is serviceable for the attachment of the hose to a dispensing faucet (not shown) of a bar fixture 10 or to a container from which the liquid is dispensed into the bottle A.

Mounted upon the cover 13 is an air pump of the hand operated piston type, its barrel 37 being connected with a union 38 which is made secure in the cover 13 and the piston 39 operates within said barrel 37. The stem 40 of the piston outside of the barrel 37 carries a handhold 41 so that the pump can be manually operated. The barrel 37 of the pump is built with an air feed nozzle 42 which extends into the union 38 and is equipped with a return check valve 43 so that air from the pump will enter the bottle A through the union 38 and will be checked against return flow. In this manner the contents of the bottle A can be placed under pressure for the dispensing of such liquid. The union 38 has formed therewith a pressure release extension or nipple 44 having an outlet port 45 which is controlled by an adjustable needle valve 46 the same being manually regulated and this valve engaging a seat 47 provided within the nipple 44. On engagement of the valve 46 with the seat 47 the outlet port 45 is closed so that pressure cannot escape therethrough. The nipple 44 is equipped with a pressure gage 48 of any standard type so that the pressure within the bottle A can be readily determined therefrom. The air passing through the nipple 44 will escape through the port 45 to the atmosphere. In the union 38 concentrically of the nozzle 42 and formed in the bore of said nipple is a chamber 50 so that air under pressure within the bottle A can make its escape about the nozzle 42 to the atmosphere through the port 45. It is, of course, understood that the pressure within the bottle A can be relieved on the opening of the port 45 and in doing this the bottle A can be readily filled to the desired level therein.

When the pump is operated it places the contents of the bottle A under pressure. The attachment is serviceable in the dispensing of beer or other liquid beverages.

In Figure 9 of the drawings there is shown a slight modification wherein the nipple 51 which

corresponds to the nipple 44 serves as an inlet nipple containing an inlet port 52 and a compressor coupling tip 53, the latter being equipped with a return check valve 54 so that air from a compressor (not shown) can be drawn into the nipple 51 to place the contents of the bottle A under pressure and in the use of the compressor the operation of the pump is entirely dispensed with, this being the case when the capacity of the equipment is increased.

The vacancies as provided by the mutilated bead or rib 11 on the bottle neck 10 affords clearances for the post 21 when fastening the cover 13 to the said bottle neck.

The liquid contained within the bottle A is dispensed therefrom through the spout 55 and the flow of such liquid is controlled by the valve 29 as herein before described. This spout 55 is applied when the hose 34 is removed.

What is claimed is:

Means for mounting a pump and faucet pressure-tight upon a container, including a cylindrical neck integral with the container, an annular bead extending circumferentially around the neck about midway between the container and the rim of the neck, said bead having a pair of gaps disposed diametrically opposite each other therein, a lug on the neck rising from the bead midway between the gaps and extending to the top of the neck, a disc cover for supporting the pump and faucet on the neck having a skirt telescopically receiving the neck, there being a notch formed in the skirt receiving the lug and anchoring the cover against rotation, a clamp ring having a pair of half circular sections encircling the neck and having inwardly directed bottom flanges disposed beneath the bead, a resilient gasket on the flanges engaging underneath and embracing the bead and preventing the clamp ring from damaging the neck, the clamp ring sections having perforated ears disposed at the gaps in the bead, adjusting screws for drawing the ears together to tighten the clamp ring, binding posts pivoted at the lower ends on said adjusting screws, the cover having a peripheral flange provided with seats receiving the upper ends of the binding posts, nuts on the binding posts engaged with the cover to hold the cover tightly down upon the neck, and a gasket between the cover and the rim of the neck compressed by the cover to prevent pressure leakage from the container.

LEONARD W. VALENTINE.
